UNITED STATES PATENT OFFICE.

LAJOS FERENCZY, OF EASTON, PENNSYLVANIA.

ENVELOP-MOISTENER.

1,028,011.

Specification of Letters Patent. Patented May 28, 1912.

Application filed September 6, 1911. Serial No. 647,868.

To all whom it may concern:

Be it known that I, LAJOS FERENCZY, a subject of the King of Hungary, residing at Easton, in the county of Northampton and State of Pennsylvania, have invented certain new and useful Improvements in Envelop-Moisteners, of which the following is a specification, reference being had therein to the accompanying drawing.

10 This invention relates to envelop moisteners, and has for its object to provide a device of such class in a manner as is hereinafter set forth, including means for efficiently supplying water to a moistening brush when occasion so requires, so that the adhesive of the envelop can be quickly moistened.

Further objects of the invention are to provide an envelop moistener which is simple in its construction and arrangement, 20 strong, durable, efficient and convenient in its use, readily set up and inexpensive to manufacture.

With the foregoing and other objects in view, the invention consists in the novel construction, combination and arrangement of parts as hereinafter more specifically described and illustrated in the accompanying drawings wherein is shown an embodiment of the invention, but it is to be understood 30 that changes, variations and modifications can be resorted to which come within the scope of the claim hereunto appended.

In the drawings, wherein like reference characters denote corresponding parts throughout the several views—Figure 1 is a vertical sectional view of an envelop moistener in accordance with this invention with the outlet of the water reservoir closed. Fig. 2 is an elevation partly in section of the 40 device with the outlet of the water reservoir open. Fig. 3 is a section on line III—III looking in the direction of the arrow.

Referring to the drawings in detail, 1 denotes a relatively long annular receptacle 45 open at its lower end and having its upper end formed with an inwardly extending threaded collar 2 constituting an inlet for the water reservoir 3, the latter being formed by the receptacle 1. The inlet, which is indicated by the reference character 4, is closed through the medium of a hollow threaded plug 5 which engages with the threads of the collar 2. Interposed between the lower end of the plug 5 and the bottom 55 of the collar 2 is a resilient washer 6 which forms a closed joint at the inner terminus of

the plug 5 with respect to the inner terminus of the collar. The lower end of the receptacle 1 has its wall formed with a series of threads 7 for a purpose to be presently referred to. 60

Connected to the lower end of the body portion 1 in a manner to be presently referred to, is an inverted conical-shape container 8, in which is arranged a sponge 9. 65 The container 8 at its lower end is formed with a depending nipple 10 in which extends the upper end of a moisture applying brush 11. The top of the container 8 is formed of two parallel spaced disks 12 which are integral with the inner face of the body of the container and each of which has a centrally disposed opening 13 constituting a water outlet for the reservoir 3. Formed integral with and projecting upwardly from 70 the upper disks 12 is a threaded collar 14 engaging with the threads 7 of the body portion 1 for coupling the container with said body portion and for further positioning the disks 12 so that they will form the bottom of the reservoir 3. The openings 13 are closed through the medium of a slide 15 which is interposed between the disks 12 and extends through a slit 16 formed near the top of the container 8. The slide 15 at 75 its outer end carries a thumb piece 17 to permit of the shifting of the slide to open and close the openings 13.

Water is supplied from the reservoir 3 to the sponge 9 when the slide 15 is shifted 80 outwardly to open the outlet of the reservoir 3 and after sufficient water has been supplied to the sponge 9 the slide 15 is shifted inwardly to close the outlet. The brush 11 takes up the water from the sponge 95 9 and applies the same to the adhesive upon the envelop. The body portion 1 not only constitutes a reservoir for the water 18, but also provides a handle for the operator when using the moistening device. The plug 5 100 has its periphery knurled as at 19 to facilitate the convenient removal and replacing of the plug when occasion so requires.

What I claim is:—

An envelop moistener comprising a receptacle constituting a water reservoir and a handle, a container provided at one end with an outlet and at its upper end with a top formed with a valve chamber, means projecting from the container and engaging 110 with the lower end of said receptacle for connecting the container to the receptacle, the

top of said container provided with openings for establishing communication between the reservoir and the interior of the container, said container adapted to hold an absorbent body, the top of said container constituting the bottom for said reservoir, a brush mounted in and projecting from the outlet to said container, and a valve arranged in said chamber for normally clos-

ing said openings and capable of being shifted to establish communication between the container and the reservoir.

In testimony whereof I affix my signature in the presence of two witnesses.

LAJOS FERENCZY.
